UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed September 26, 1922. Serial No. 590,642.

To all whom it may concern:

Be it known that I, ALONZO E. RHOADES, a citizen of the United States, and a resident of Hopedale, county of Worcester, 5 State of Massachusetts (whose post-office address is Hopedale, Massachusetts), have invented an Improvement in Feeler Mechanism for Looms, of which the following description, in connection with the accompanying drawing, is a specification, like characters on the drawing representing like parts.

This invention relates to a feeler mechanism for effecting automatically a change in 15 the operation of the loom when the filling in the working shuttle has become substantially exhausted but while sufficient filling still remains on the filling carrier to insure the weaving of perfect cloth. The change in 20 the operation of the loom thus effected may, for example, be the stopping of the loom or it may be and frequently is the replenishment of a fresh supply of filling such as takes place in the well known automatic filling 25 replenishing loom. Various forms of feeler mechanism have been designed for accomplishing this object but this invention relates more particularly to that type of feeler mechanism employing what is commonly termed a "needle-feeler". This type 30 of feeler mechanism comprises a feeler member having a small point which is adapted to sink into the mass of filling upon each detecting beat of the lay without effecting 35 the operative movement of the feeler member until the filling has become exhausted to the required degree whereupon the point of the feeler member comes into contact with the hard surface of the filling 40 carrier and upon the ensuing beat up of the lay is given an operative movement.

One object of the present invention is to provide a feeler mechanism of the needle type in which this needle or penetrating 45 feeler member is normally held in a retracted position so as not to engage and penetrate or sink into the filling thus preventing any injury or damage being done thereby to the filling and in which this penetrating 50 member is only projected so as to engage the filling when the filling has been exhausted to a predetermined extent or is approaching the degree of exhaustion de-

sired for effecting the change in the operation of the loom.

55

Another object of the invention is to provide a feeler mechanism of this type in which the penetrating member is brought from its normal retracted position into its position to engage with the filling by means 60 of a shuttle impinging feeler member or a member which when the filling has become exhausted to a predetermined degree comes into contact with the face of the shuttle or shuttle box wall.

65

A further object of the invention is to provide in this type of feeler mechanism a governing or controlling feeler member which is given an indicating movement upon the exhaustion of the filling to a predetermined extent and thereby or therethrough acts to bring the filling penetrating member into position to engage and feel the filling.

70

A further object of the invention is to provide a feeler mechanism of this type 75 comprising a filling penetrating member, a filling impinging member, a controlling or governing member such as a shuttle impinging member and an actuator together with means associated with the filling penetrating member, the governing member and the actuator acting to maintain the filling penetrating member retracted and the actuator inactive until the filling is sufficiently exhausted to effect the movement of the governing member and then acting to maintain the filling penetrating member projected until the filling is sufficiently exhausted to permit the filling penetrating member to engage the filling carrier and then acting to move the actuator into actuating position, the said means preferably being in the form of a lever engaging the filling penetrating member and fulcruming successively on the actuator and on the governing member or 85 shuttle impinging member.

80

A further object of the invention is to provide a feeler mechanism of this type in which the filling penetrating member is normally retracted and does not engage 100 with the filling until the filling is approaching substantial exhaustion so that there is little or no danger of the point of the penetrating member cutting or injuring the filling.

105

A further object of the invention is to

provide in this type of feeler mechanism a shuttle impinging member moving rectilinearly and thus having no gouging action tending to wear the face of the shuttle.

5 In some aspects the present invention is subsidiary to the invention made the subject of my application, Serial No. 590,641 filed concurrently herewith. The general nature and the objects of the present invention will 10 appear more fully from the description and drawings and will be particularly pointed out in the claims.

In the drawings:

Fig. 1 is a top plan view of a preferred 15 form of feeler mechanism embodying the invention;

Fig. 2 is a side elevation of the construction shown in Fig. 1;

Figs. 3, 4, 5 and 6 are enlarged details 20 chiefly in top plan view showing successive positions of the main elements of the feeler mechanism in relation to a filling carrier as the filling is diminished thereon.

As the general construction and operation 25 of feeler mechanisms of this general type, and as the construction and operation of looms of different types to which such feeler mechanisms may be applied, are both well known and familiar to those skilled in the 30 art it will only be necessary to illustrate and describe in detail those features immediately concerned with the present invention.

The preferred form of feeler mechanism illustrated is of a form particularly adapted 35 for an automatic replenishing loom of the well known "Northrop" type and for governing the replenishing operation by which a fresh filling carrier is forced into the shuttle on the lay when the running filling carrier has become substantially exhausted. Such automatic filling replenishing mechanism is usually set into operation by the forward movement of the end of a controller arm 1 and the object of the feeler mechanism 40 is to give this movement to the controller arm when the filling in the shuttle has reached substantial exhaustion.

The feeler mechanism is shown as comprising a feeler stand having two main 50 parts, a base 2 and a top 3 secured together by screws 4 and supported upon a bracket 5 by bolts which bracket is again in turn secured to the breast beam or other fixed portion of the loom opposite the detecting side 55 of the loom. The lay 6 is shown as provided with the usual shuttle box 7 having an opening 8 to permit the passage of certain of the feeler elements and in which the shuttle 9, also having an opening 10 in its side to 60 permit the passage of certain of the feeler elements, is boxed at the detecting side of the loom. The shuttle is shown as carrying a filling carrier or bobbin 11 of usual form. The main or operative parts of the feeler 65 mechanism of this invention comprise a fill-

ing impinging member, a filling penetrating member, a governing or controlling member such as a shuttle impinging member, and a controller actuator all carried by a feeler slide and each having a movement relatively 70 to the others.

The feeler slide is shown as a flat metal plate 12 mounted in a groove in the feeler stand so as to slide longitudinally toward and from the lay. The forward portion 13 75 of the feeler slide is smaller than the rear portion thus forming a shoulder 14 against which a spring 15 surrounding the portion 13 abuts. This spring also abuts against a shoulder 16 at the forward end of the feeler 80 stand and thus acts normally to project the feeler slide toward the lay.

The end of the controller 1 is guided in a longitudinal slot formed in the feeler stand and a stop lug 18 carried by the feeler slide 85 acts to insure the movement of the controller arm 1 into its rearward or normal position.

The actuator is in the form of a bell crank lever fulcrumed at 19 on a post or bracket 20 projecting upwardly from the feeler 90 slide. The long arm 21 of the actuator projects forwardly and is provided with a forked end 22 while the shorter arm 23 projects downwardly nearly to the plate 12. A vertical plunger 24 normally depressed by 95 a spring 25 is mounted in a bracket 26 at the rearward end of the feeler stand and acts normally to hold the actuator with its longer arm 21 depressed so that during the reciprocations of the feeler slide this arm will 100 pass beneath the end of the controller 1.

The filling impinging member is formed by the long wide flat surface 27 at the rear end of the feeler slide and the cover plate 28 which is secured by screws 29 to the rearward end of the feeler slide. During the ordinary operation of the loom this is the only part which contacts with the filling and as the surface 27 is comparatively large and smooth there is little danger of any injury 110 being done to the filling by its contact therewith.

The filling penetrating member or needle feeler is a small sharp point 30 formed on the end of a bar 31 which has a substantially 115 rectilinear sliding movement in a groove formed between the plate 12 and cover plate 28.

The governing or controlling feeler is in the form of a threaded stud 32 having a rounded head 33 to engage preferably with the face of the shuttle. This stud is adjustable longitudinally in a block 34 and is locked in adjusted position by a lock nut 35. The block 34 is carried upon a slide fitting 120 between the plate 12 and cover plate 28 and is thus guided rectilinearly and longitudinally of the feeler slide. This insures a direct contact with the shuttle wall and eliminates any wear or gouging of the shuttle 125 130

wall. A spring 37 seated between the block 34 and bracket 20 acts normally to hold the shuttle impinging member and its slide in rearward or projected position.

5 The specific means illustrated as an embodiment of the invention for governing or controlling the relative movements of the filling penetrating member and actuator from the governing or controlling member 10 or shuttle impinging member is a lever 38 located between the plate 12 and cover plate 28. One end of this lever is pivoted at 39 to the forward end of the filling penetrating member 31 and at its other end is pivoted 15 at 40 in the slide 36 of the shuttle impinging member. At its central portion this lever 38 is provided with a curved projection 41 which seats against the shorter arm 23 of the actuator lever. During the normal 20 operation of the loom the parts are in the position shown in Figure 1 with the filling penetrating member retracted and as the feeler slide is pushed forwardly by the contact of the filling with the filling impinging member 27 the arm 21 of the actuator rides beneath the controller 1. If, for any 25 reason, the filling penetrating member should project beyond the surface 27 it is pushed forward or retracted by slight contact with the filling. The successive steps in the operation of the feeler mechanism will best be understood by reference to the detailed illustrations of Figures 3, 4, 5 and 6.

In Figure 3 the parts are shown in the 35 position which they normally have when the filling carrier is filled or substantially filled with filling. At every other beat up of the lay, or when the shuttle is at the detecting side of the loom, the filling 42 engages the 40 filling impinging face 27 and moves the feeler slide forwardly as set forth.

In Figure 4 the filling 42 is assumed to have reached a point approaching substantial exhaustion when it is desired that 45 an accurate feeling operation should be performed so as to indicate substantial exhaustion. Under these circumstances the shuttle impinging member 32 is adjusted so that the head 33 will contact with the wall 50 9 of the shuttle. When this contact takes place on the next detecting beat of the lay the shuttle impinging member contacting with the shuttle is moved slightly forwardly 55 rocking the lever 38 on the fulcrum 41 seated against the actuator. The actuator does not move because the spring 37 is of much lighter force than the spring 25. This rocking movement of the lever 38 projects the penetrating member 31 slightly and the point 30 60 sinks into the filling. This operation continues with the point 30 sinking deeper into the filling at each detecting beat up of the lay until the position is reached which is illustrated in Figure 5 wherein the penetrating member has reached its greatest

amount of projection and it has just barely sunk through the last layer of filling 42 into contact with the filling carrier 11.

In Figure 6 the filling 42 has woven off to such an extent that only an amount remains on the filling carrier sufficient to make one, two or more picks as desired and when this takes place as the detecting beat up of the lay occurs the hard surface of the filling carrier 11 contacting with the penetrating 75 point 30 forces the filling penetrating member 31 forwardly in the feeler slide and as the shuttle impinging member 32 is held by the shuttle wall the lever 38 now fulcrums on its pivotal connection 40 and the previous 80 fulcrum point 41 moves bodily forwardly rocking the actuator and lifting the arm 21 so that its forked end 22 comes opposite the end of the controller arm 1 and as the forward movement in the feeler slide continues 85 the controller arm 1 is carried forwardly initiating the desired change, such as filling replenishment, in the operation of the loom.

Thus it will be seen that the filling penetrating member engages only with the filling when the filling is nearing the point of substantial exhaustion and thus does not contact with the filling during the normal operation of the loom, that its action is controlled or governed by an adjustable member such as the shuttle impinging member 32, and when the filling penetrating member does begin its detecting action it acts but a short time before the required degree of exhaustion of the filling is reached when 90 having engaged with the smooth hard surface of the filling carrier it acts directly and firmly to raise the actuator into actuating or operative position.

There is thus presented a very simple, 105 efficient and desirable form of feeler mechanism which may be readily and accurately adjusted to the required conditions and which does not act to injure or damage the filling.

Having thus described my invention, what I claim as new, and desire to secure by Letters Patent, is:

1. A feeler mechanism for looms comprising a longitudinally movable support, means 115 acting normally to project the support toward the shuttle, a filling impinging member carried by the support, a filling penetrating member, a shuttle impinging member mounted to move rectilinearly and longitudinally of the support, an actuator acting when moved into actuating position to initiate a change in the operation of the loom, the said filling penetrating member, shuttle impinging member and actuator 120 each carried by the support and movable relatively to the support and to each other, a lever engaging at separated points the filling penetrating member, the shuttle impinging member and the actuator, the said 125 130

lever remaining inactive until the filling has been sufficiently exhausted to allow the shuttle impinging member to contact with the shuttle upon the beat-up and thereafter fulcrumming on the actuator until the filling has been sufficiently exhausted to allow the filling penetrating member to engage the filling carrier and then fulcrumming on the shuttle impinging member to move the actuator into actuating position.

2. A feeler mechanism for looms comprising a longitudinally slidable feeler slide, means acting normally to project the feeler slide toward the shuttle, a filling penetrating member mounted in and longitudinally slidable relatively to the feeler slide, a filling impinging member carried by the feeler slide, a shuttle impinging member mounted in and longitudinally slidable relatively to the feeler slide, an actuator carried by the feeler slide, movable relatively thereto, standing normally in inactive position, and acting when moved into actuating position to initiate a change in the operation of the loom, and a lever pivoted at its ends to the filling penetrating member and the shuttle impinging member and fulcrumed intermediate of its ends on the actuator whereby until the filling is sufficiently exhausted to permit the shuttle impinging member to contact with the shuttle the filling penetrating member remains retracted and the

actuator inactive and whereby when the filling is sufficiently exhausted to cause the shuttle impinging member to contact with the shuttle the lever is rocked on the actuator to project the filling penetrating member and whereby when the filling is sufficiently exhausted to enable the filling penetrating member to engage the filling carrier the lever is rocked on its connection to the shuttle impinging member and moves the actuator into actuating position.

3. A feeler mechanism for looms comprising a rectilinearly slidable feeler slide, means acting normally to project the feeler slide toward the shuttle, a filling penetrating member mounted in and longitudinally slid able relatively to the feeler slide, a shuttle impinging member mounted in and rectilinearly and longitudinally slid able relatively to the feeler slide, and means for controlling the position of the filling penetrating member from the shuttle impinging member.

4. A feeler mechanism for looms comprising a filling penetrating member, a rectilinearly movable shuttle impinging member and means for controlling the position of the filling penetrating member from the shuttle impinging member.

In testimony whereof, I have signed my name to this specification.

ALONZO E. RHOADES.
